1

This invention relates to mass spectrometry and more specifically to methods and apparatus for varying the resolving power of a mass spectrometer by electrical means.

In mass spectrometry, a mixture to be analyzed is ionized, at least in part, by electron bombardment. The ions are then segregated in accordance with their mass-to-charge ratio and all the ions of a given mass-to-charge ratio are discharged at a collector electrode. The segregation may be accomplished in various ways. One common technique, and the one with which the present invention is concerned, involves propelling the unsegregated ions as a heterogeneous beam through a magnetic field, the direction of the field being transverse to the direction of ion travel. In the magnetic field, the path of the ion beam is bent with ions of differing mass-to-charge ratio assuming different radii of curvature so that the heterogeneous beam is separated into a plurality of essentially homogeneous beams. A single ion beam is focussed on and discharged at a collector electrode, the discharge current being a function of the partial pressure in the original sample of the particles from which the ions of the beam are derived. Frequently the mass spectrum is scanned by successively focusing the several spatially separated beams on the collector electrode.

In the conventional instrument, the resolution of the several beams is accomplished by a barrier placed in front of the collector electrode and having a narrow slit through which ions must pass to reach the collector. This slit is commonly referred to as the resolving slit and is oriented with its major axis parallel to the magnetic field. Ions of differing mass-to-charge ratio are focussed on the resolving slit by varying the magnitude of the ion propelling field or by varying the magnetic field strength. The resolving power of such an instrument is a function of the width of the resolving slit, i. e. the length of its minor axis transverse to the direction of the magnetic field. By varying this dimension, as by substitution of a barrier having a different size slit or by mechanical adjustment of the slit size, the resolving power of the mass spectrometer may be varied.

I have now discovered a method for varying the resolving power electrically together with apparatus designed for carrying out the method in the most effective manner. As will become more apparent in the description of the accompanying drawings, there is a need for some simple and effective method of varying the resolving power of a mass spectrometer in order that the instru-

2

ment may be operable over a wide range of mass numbers. Thus the resolving power most effective at lower masses is inadequate for resolving higher masses, whereas the higher resolving power necessary for the higher masses interferes with analysis of the lower masses. In one aspect, the invention contemplates a method of varying the resolving power of a mass spectrometer in which an ion beam is focussed through a resolving slit and onto a collector electrode which comprises developing in the region between the resolving slit and the collector electrode an electrostatic field having a component parallel to the direction of ion travel and in opposition to ion travel to the collector electrode and a component transverse to the direction of ion travel and parallel to the minor axis of the resolving slit, with the transverse component being of zero intensity at the axis of symmetry, and controlling the magnitude of the electrostatic field so that an ion beam of a given energy can traverse the distance between the resolving slit and the collector electrode only in a path of a width not exceeding the minor axis of the resolving slit and centered on the axis of symmetry.

By shaping the electrostatic field so as to form a saddle, i. e. a region where the potential will be at a maximum in the longitudinal direction and a minimum in the transverse direction and on the axis of symmetry, the field functions as a virtual resolving slit when the potential at the saddle point approaches the potential of the point from which the ions originated in the ion source. If the saddle is wider than the resolving slit, that is, if the region over which the opposing potential is less than the starting potential of the ions is wider than the minor axis of the resolving slit, resolving power of the mass spectrometer will be determined by the resolving slit. If the electrostatic field strength is increased, the saddle is narrowed, i. e. the transverse area thereof having an opposing potential less than the potential energy of the ions is restricted to a width less than the resolving slit and the electrostatic field then determines the resolving power of the instrument.

The energy of an ion is determined by the potential existing at the point of ion formation. In the accelerating field, ions gain kinetic energy at the expense of potential energy, the total energy remaining constant. Hence, when the ions enter the opposing electrostatic field between the resolving slit and the collector, they give up kinetic energy, if necessary, to the point where their initial potential energy is restored. If,

however, a particular ion seeks to traverse the opposing field in a region where the bucking potential exceeds the potential energy of the ion, it will be blocked. As the opposing potential approaches the potential energy of a particular ion, the saddle point for that ion narrows about the axis of symmetry. This in effect narrows the available path between the resolving slit and the collector for that ion. As this path becomes narrower than the resolving slit, the resolving power of the instrument is increased.

The use of an opposing electrostatic field in the region of the collector electrode is not new in mass spectrometry. Such a field has been established by means of an electrode located between the resolving slit and the collector electrode and maintained at a potential opposing ion flow towards the collector electrode. However, the purpose of this prior use has been entirely different from the principles of the present invention and has related solely to the blocking of "ghosts," e. g. ionized fragments resulting from metastable transitions, or ions that have been slowed through collision with gas molecules or the walls of the analyzer. These ghosts have been found to have an energy less than the energy of the ions of a given mass-to-charge ratio with which they are associated. The development of an electrostatic bucking potential of sufficient magnitude to block such lower energy ghost ions has been found to improve the operation of the mass spectrometry. However, the use of such a potential to vary the resolving power of a mass spectrometer is novel there having been no effort made to establish a field to act as a virtual resolving slit so as to restrict the path of the ions under investigation.

For the purpose of this invention, I have found that a single electrode disposed between the resolving slit and collector electrode is not entirely satisfactory for developing the type of electrostatic field necessary to vary the instrument's resolving power.

Accordingly, the invention also contemplates in a mass spectrometer having an ionization chamber, means for ionizing molecules in the chamber, an analyzer, means for propelling ions from the ionization chamber as a beam through the analyzer, means for sorting the ions of the beam in the analyzer according to their specific mass, and a target electrode for collecting ions impinging thereon, the combination comprising a conductive barrier disposed between the analyzer and the target electrode and having a resolving slit therein through which ions must pass in traveling from the analyzer to the collector, a plurality of interconnected parallel electrodes disposed between the barrier and the target and having slits therein aligned with and wider than the resolving slit, and means for impressing on the said plurality of electrodes a potential opposing ion travel from the barrier to the target.

I have found that a plurality of parallel and interconnected electrodes permits development of a bucking field having optimum shape for the purposes of this invention.

The invention will be more clearly understood from the following detailed description thereof taken in conjunction with the accompanying drawing wherein:

Fig. 1 is a schematic diagram of a mass spectrometer adapted to the practice of the invention;

Fig. 2 is an enlarged view of the collection end of the mass spectrometer of Fig. 1 showing the

nature of the field established between the collector electrode and resolving slit;

Fig. 3 is a diagram showing a plot of the transverse component of the electrostatic field in the region of the saddle point and illustrating its effect as a virtual resolving slit;

Fig. 4 is a graph showing the variation in resolving power and discharge current intensity as the transverse potential component of the electrostatic field is varied; and

Figs. 5 and 5A illustrate sections of actual recordings of ion discharge currents showing the effect of variation in the width of the effective resolving slit in the case of a low mass number spectrum and in the case of a high mass number spectrum respectively.

Referring to Fig. 1, the spectrometer there shown diagrammatically comprises a cylindrical head 10 which connects with a sample inlet tube 11 made of insulating material. Within the head, in the path of the gas entering from the inlet tube, there is a pusher or repeller electrode 12 in the form of a conductive plate insulated from the rest of the apparatus.

An electron beam 13 is produced within the head in the space immediately following the electrode 12 by means of an electron gun (not shown). The region of the electron beam is referred to as the ionization chamber 14, since gas molecules entering the head from the inlet tube 11 are ionized by the electron beam in this region. The front of the ionization chamber is formed by an intermediate propelling or collimating electrode 15 which is electrically connected to the head and is provided with a slit S1 that is substantially in line with the pusher electrode and with the path of the electron beam. A second propelling or collimating electrode 16 is spaced in front of the first electrode by a ring 17 of insulating material and is provided with a slit S2 aligned with the slit S1 and the electron beam. The head 10 opens into an analyzer tube 18 through the slit S2. The analyzer tube in the illustrated type of spectrometer is semi-circular in shape and encloses an analyzer chamber 19.

The opposite end of the analyzer tube 18 is provided with an exit or resolving slit 20 which gives access to an ion collector or target 21.

The head 10 of the spectrometer, analyzer tube 18 and the collector electrode 21 are enclosed within an envelope 23 through a wall of which the sample inlet tube 11 projects. A high degree of vacuum is maintained within the envelope by means of vacuum pumps (not shown) connected to a gas outlet 24. Within the envelope and substantially surrounding the target is a metallic shield 27 in the form of a cylinder with a disk at its end interposed between the end of the analyzer tube and the target and having an aperture or slit 28 in line with the target and the resolving slit at the end of the analyzer tube.

Intermediate the resolving slit 20 and the shield 27 there is mounted, in accordance with the present invention, a plurality of interconnected parallel electrodes 29 which function in the manner hereinafter explained. The entire instrument is maintained in a magnetic field transverse to the direction of travel of the ion beam by means of a magnet (not shown). A battery or other direct current supply 30 is connected in an energizing network across a potentiometer 31. The positive end of this potentiometer is connected through a slider 31A and a switch 32 to a capacitor 33. A potential dividing network is connected across this capacitor and

takes the form of a potentiometer 34 connected in series with a second resistor 35. A lead 36 connected intermediate the potentiometer 34 and resistor 35 is connected to the terminal propelling electrode 16 and to ground. Since the terminal propelling electrode 16 is electrically connected to the analyzer tube, the latter is also grounded. Potentiometer 34 has a first slider 34A connected to the intermediate propelling electrode 15. Pusher electrode 12 is connected to the potential dividing network by means of a slider 38 for reasons hereinafter explained.

A second adjustable tap 34B of the potentiometer 34 is connected to the electrodes 29 in the collection end of the mass spectrometer. By connecting the pusher electrode to the potentiometer through slider 38 rather than to the positive end of the potentiometer, as is the conventional practice, the electrodes 29 may be operated at a somewhat higher positive potential than the pusher electrode. Such relationship constitutes preferred practice for the reason that the potential on the axis of symmetry of the electrode 29 is inherently somewhat lower than the potential impressed on the electrode and for optimum results it is desirable to be able to raise this potential (at the axis of symmetry) near to that of the pusher electrode. This can only be done if electrode 29 is at a higher potential than the pusher electrode.

The target or collector electrode 21 is connected to ground through a high resistance 42. This resistance is shunted by an amplifying and indicating or recording apparatus 44 which is preferably of the negative feed-back type so as to minimize the effect of the high resistance. The shield 27 is likewise connected to ground and hence the barrier in which the resolving slit 20 is located and the shield 27 are at the same potential as the terminal accelerating electrode 16, which is likewise grounded. A variable capacitor 46 may be connected from the target to the circuit supplying the propelling potentials. The capacitor is connected between the target and the resistance 42 so that the path to ground is from the target through the capacitor 46 and resistor 35. Although the incorporation of capacitor 46 in the output circuit forms no part of the invention which is in no way limited to the particular output circuit shown in the drawing, the capacitor is desirable since it provides means for balancing out the effects of capacitance coupling between electrodes 21 and 29.

In the operation of the spectrometer, a sample of gas to be analyzed is admitted to the ionization chamber through the gas inlet tube. Molecules of the gas sample are bombarded and ionized by the electron beam. The resulting ions are propelled as an unsorted ion beam B into the analyzer tube 18 by means of electrical potentials established between the pusher and the two collimating electrodes by the electrical circuit as described. Thus, slits S1, S2 in the propelling electrodes 15, 16 respectively, through which the ions pass, cause the ions to immerge into the analyzer as a thin ribbon, a cross section of which is defined approximately by the shape of the slits. In the analyzer the unsorted ion beam is separated into a plurality of diverging homogeneous ion beams B1, B2, B3 under the influence of the magnetic field transverse to the travel of the beams.

One of the ion beams is focussed on the resolving slit 20 and passes through this slit to strike the collector electrode. Discharge of the

beam at the collector electrode develops a discharge current which is amplified and recorded in the conventional manner. The path of the ion beams with respect to the resolving slit may be altered to focus one or more of the other ion beams on the resolving slit by varying either the magnetic field or the propelling potentials. The latter method is preferred and is accomplished as follows. The switch 32 in the energizing network is closed and the condenser 33 is charged to an appropriate level. The switch is then opened and the condenser is permitted to discharge through the potential dividing network and through the propelling electrodes in the head of the spectrometer. In this way the propelling potentials between the several electrodes gradually decay while maintaining constant relative values. The potentials in the head may be adjusted relative to each other by suitable adjustment of the slider 34A of the potentiometer 34.

As above described, the series of slits provided by the electrodes 29 intermediate the resolving slit and collector electrode makes it possible to vary electrically the apparent width of the resolving slit if these electrodes are maintained at a certain potential with respect to the potential of the ion source. At some point near the axis of symmetry of the electrodes 29 there exists a saddle point in the electrical potential, that is, the potential is at a maximum in the longitudinal direction and a minimum in the transverse direction.

The character of the electrostatic field between the resolving slit 20 and the shield 27, as established by the electrodes 29, is illustrated in Fig. 2 which is an enlarged view of the collection end of the spectrometer. Equipotential lines 48 are sketched in the diagram of Fig. 2 showing the saddle point to be approximately in the region of the point S. If a single electrode is used in place of the plural electrodes 29, the configuration of the field is altered and different operation is obtained. The relationship of the resolving slit to the ion beams B1, B2, B3 is shown schematically above the resolving slit 20.

A plot of the transverse potential in the region of the saddle point is shown in Fig. 3 for two values V1, V2 of voltage applied to the electrodes 29. The horizontal axis of the plot represents the energy of the ions of a given beam in volts. Hence any of the ions of this particular beam which approach the saddle point at a distance from the axis of symmetry such that the potential curve V1 is above the energy of the ions, will not be able to penetrate the field. With the potential V1, only those ions will penetrate the field whose physical distance from the axis of symmetry is less than

$$\frac{D_1}{2}$$

where D1 is the transverse dimension of that part of the field which is at a potential less than the potential energy of the particular ion. If the transverse potential is at the V2 level, only those ions of a potential energy represented by the horizontal axis will pass, whose distance from the axis of symmetry is less than

$$\frac{D_2}{2}$$

Hence, by increasing the voltage applied to the electrodes 29 so that the transverse component of potential is altered from V1 to V2, as represented on the diagram of Fig. 3, the virtual resolving slit developed by the electrostatic field will be de-

creased by an amount equal to D_1 minus D_2 and the resolving power of the mass spectrometer will be increased proportionately provided that D_1 is shorter than the minor axis of the resolving slit 20.

Fig. 4 is a plot of the resolving power of the mass spectrometer and the ion beam intensity at the collector electrode as the voltage on the electrodes 29 is increased. For a time, the effective width of the virtual slit formed by the electrostatic field is greater than the actual width of the resolving slit 20 so that any increase in voltage applied to the electrodes 29 has no effect on the resolving power. At a certain critical potential represented by the point X on the horizontal axis of the plot of Fig. 4, the effective width of the virtual slit becomes equal to the width of the resolving slit. Any increase in potential applied to the electrodes 29 above the critical value X increases the resolving power by reducing the width of the virtual slit to less than the width of the resolving slit. The ion beam intensity curve is seen to remain constant considerably beyond the critical potential X. This is so because in the region between potential X and potential Y the virtual slit, although narrower than the resolving slit, is still wider than the ion beam itself. When the potential on the electrodes 29 is raised above the point where the transverse component is at the potential Y, the virtual slit becomes narrower than the ion beam and the ion intensity drops rapidly to zero. Thus there is a range of operation between potentials X and Y in which the resolving power is a function of the voltage applied to the electrodes 29 and yet in which there is no loss in ion beam intensity.

In addition to providing means for varying the resolving power of the mass spectrometer, the electrodes 29 also act as an energy filter to suppress meta-stable ions in the manner taught in the prior art, this function however being of secondary importance to the primary function of providing means for varying the resolving power.

The advantages of being able to vary resolving power of a mass spectrometer without altering the construction of the instrument are not immediately apparent. It might seem that if a high resolving power is desirable in one set of circumstances, that an instrument having such a high resolving power would be satisfactory under all circumstances. However, this is not the case and the reasons why this is not so are illustrated in Figs. 5 and 5A.

One important reason why the resolving power necessary to separate components of large mass (see Fig. 5A) is not ideal for components of low mass (see Fig. 5) is the recording speed reduction necessitated by an increase in resolving power. The spatial separation between ions of low mass is sufficiently great to tolerate low resolving power and high recording speed which is desirable as resulting in faster analysis.

In the analysis of the gases of comparatively low molecular weight, say of 70 or 80, or below, ions of the same mass number are formed from more than one type of molecule. Consider for example the mass number 44. Ions of this mass number are formed from ionization of carbon dioxide and from ionization of propane, the atomic weights of the respective ions being 44.04 and 44.076 respectively. In any mass range it is desirable to operate at such a resolving power that all ions having the same mass number can pass through the resolving slit at one time. In Fig. 5 trace A shows an actual trace obtained from the spectrum of ions of mass number 44 derived from

carbon dioxide and propane with the effective resolving width being greater than the spectrum width. The superposition of the CO_2 and C_3H_8 peaks is evident, the solid trace being a composite of the individual peaks shown in dotted lines.

Trace B of Fig. 5 shows the result of analyzing the carbon dioxide propane mass number 44 spectrum in an instrument in which the effective resolving slit is narrower than the spectrum width. In this circumstance, the two peaks are partially resolved but the overlapping precludes determination of the relative concentrations since it is difficult to tell the true height of either peak. This overlapping effect is shown by the dotted lines which have been sketched into the trace B, the height of each peak being due in part to the height of the adjoining peak.

When it becomes a question of separating between ions of differing mass number, the resolution required is a function of the distances between adjacent masses for any given magnetic field strength. This distance is a function of the reciprocal of the molecular weight of the ions and hence as the mass increases, the distance between adjacent peaks decreases. In the lower molecular weights, as represented by Fig. 5, there is sufficient spread between ions of differing mass number that they may be adequately resolved in an instrument having a resolving power sufficient to obtain the linear superposition illustrated by trace A in that figure. However, if, for example, it is desired to analyze the isotopes of mercury which have mass numbers of 196, 198, 199, 200, 201, 202 and 204, the distances between the ion beams of adjacent masses is so small that a resolving power of the order of magnitude of that employed to obtain the trace A of Fig. 5 is not sufficient to resolve the mercury isotopes. This situation is illustrated by the trace A in Fig. 5A wherein, with the possible exception of the mass 204 peak, it is evidently impossible to determine the concentration of the other mercury isotopes from the trace. This is because the effective resolving slit is wider than the physical spacing between adjacent masses.

Now if this effective resolving slit is reduced so that it is narrower than the spacing between adjacent masses, a trace B is obtained wherein complete resolution between each of the mercury isotopes is achieved. The isotope 196 is present in such small proportions; in order of magnitude of one-tenth of one percent, that it does not show up on either of the traces A and B.

It should be obvious from the foregoing explanation that the utility of a mass spectrometer for analyzing mixtures over a wide mass range is greatly increased by the ability to vary its resolving power in accordance with the mass range of the particular sample under investigation and that the same increase in utility is not achieved by pre-establishing the resolving power of the instrument at the high value necessary to resolve ion beams of comparatively large mass.

I claim:

1. In a mass spectrometer having an ionization chamber, means for ionizing molecules in the chamber, an analyzer chamber, means for propelling ions from the ionization chamber as a beam through the analyzer chamber, means for sorting the ions of the beam in the analyzer chamber according to specific mass, and a target electrode for collecting ions impinging thereon, the combination comprising a conductive barrier disposed between the analyzer chamber and the target electrode and having a slit therein through which ions must pass in travelling from the ana-

lyzer to the collector, an electrode disposed between the barrier and the target and having a slit therein aligned with the resolving slit, and means for impressing on said electrode a potential of a polarity opposing ion travel from the barrier to the target and of such magnitude as to prevent ion flow through the slit adjacent its boundaries.

2. In a mass spectrometer having an ionization chamber, means for ionizing molecules in the chamber, an analyzer chamber, means for propelling ions from the ionization chamber as a beam through the analyzer chamber, means for sorting the ions of the beam in the analyzer chamber according to specific mass, and a target electrode for collecting ions impinging thereon, the combination comprising a conductive barrier disposed between the analyzer chamber and the target electrode and having a slit therein through which ions must pass in travelling from the analyzer to the collector, a plurality of interconnected electrodes disposed between the barrier and the target and having slits therein aligned with the resolving slit, and means for impressing on said plurality of electrodes a potential opposing ion travel from the barrier to the target.

3. In a mass spectrometer having an ionization chamber, means for ionizing molecules in the chamber, an analyzer chamber, means for propelling ions from the ionization chamber as a beam through the analyzer chamber, means for sorting the ions of the beam in the analyzer chamber according to specific mass, and a target electrode for collecting ions impinging thereon, the combination comprising a conductive barrier disposed between the analyzer chamber and the target electrode and having a slit therein through which ions must pass in travelling from the analyzer to the collector, a plurality of interconnected electrodes disposed between the barrier and the target and having slits therein aligned with and wider than the resolving slit, and means for impressing on said plurality of electrodes a potential opposing ion travel from the barrier to the target.

4. In a mass spectrometer having an ionization chamber, means for ionizing molecules in the chamber, an analyzer chamber, means for propelling ions from the ionization chamber as a

beam through the analyzer chamber, means for establishing a magnetic field across said analyzer for sorting the ions of the beam in the analyzer chamber according to specific mass, and a target electrode for collecting ions impinging thereon, the combination comprising a conductive barrier disposed between the analyzer chamber and the target electrode and having an elongated slit therein through which ions must pass in travelling from the analyzer to the collector and oriented with its major axis parallel to the magnetic field, a plurality of interconnected electrodes disposed between the barrier and the target and having slits therein aligned with and wider than the resolving slit, means for impressing on said plurality of electrodes a potential opposing ion travel from the barrier to the target, and means for varying the potential impressed on said electrodes.

5. In a mass spectrometer having an ionization chamber, means for ionizing molecules in the chamber, an analyzer chamber, means for propelling ions from the ionization chamber as a beam through the analyzer chamber, means for sorting the ions of the beam in the analyzer chamber according to specific mass, and a target electrode for collecting ions impinging thereon, the combination comprising a conductive barrier disposed between the analyzer chamber and the target electrode and having a slit therein through which ions must pass in travelling from the analyzer to the collector, an electrode disposed between the barrier and the target and having a slit therein aligned with and wider than the resolving slit, means for impressing on said electrode a potential to develop an electrostatic field across said slit preventing ion flow except through a central region of the slit, and means for varying the magnitude of the potential to vary the dimensions of said central region.
